UNITED STATES PATENT OFFICE.

STEVE KOLARIES, OF STEELTON, PENNSYLVANIA.

RAILWAY-CROSSING GATE.

Application filed April 14, 1925. Serial No. 23,081.

This invention relates to improvements in railway crossing gates.

The primary object of the invention is the provision of a railway crossing gate which will be automatically moved into an operative position by an approaching train and held in such position by the train while passing the crossing; the gate being properly weighted to cause it to return to its inoperative position after the train has passed.

Other objects and advantages of the invention will be apparent during the course of the following description.

In the accompanying drawing forming a part of this specification and in which like numerals are employed to designate like parts throughout the same,

Figure 1 is a side elevational view of the railway crossing gate embodying this invention,

Figure 2 is a top plan view of the structure shown in Fig. 1,

Figure 3 is a longitudinal sectional view taken upon line III—III of Fig. 2,

Figure 4 is a longitudinal sectional view taken upon line IV—IV of Fig. 2,

Figure 5 is a similar view to Fig. 1, but shows the gate arms moved into their operative positions by an actuating element carried by an approaching train,

Figure 6 is a transverse sectional view taken upon line VI—VI of Fig. 2,

Figure 7 is a fragmentary transverse sectional view taken upon line VII—VII of Fig. 2,

Figure 8 is a detail longitudinal sectional view taken upon line VIII—VIII of Fig. 2, and

Figure 9 is a modified form of connecting mechanism by means of which the gate arms arranged on the opposite sides of the track may be actuated simultaneously.

In the drawings, wherein for the purpose of illustration is shown a preferred embodiment of this invention, the numeral 5 designates the railway track which is crossed at 6 by a road, or the like. Arranged on opposite sides of the track 5 at the roadway 6 are the posts 7, each of which has a gate arm 8 pivoted thereto and weighted at 9 for causing the arms to normally be arranged in their inoperative positions.

The posts 7 have rotatably mounted thereupon the grooved pulleys 10, 11, 12 and 13, as indicated in the various figures. At distantly spaced points along the track 5 are

arranged the brackets 14 which support the grooved pulleys 15, 16, 17 and 18, as illustrated.

In Fig. 1 the ends 19 of a cable A are illustrated as being connected to the gate arms 8 on one side of the track illustrated. This cable extends from the ends 19 downwardly and underneath the pulleys 10 and 11 to extend as at 20 and 21 to the pulleys 17 and 15 respectively where the said cable passes over the pulleys just referred to and then back to and beneath the pulleys 10 and 11 to its united or unbroken portion beneath the crossing 6, as indicated by the reference numerals 22 and 23, the cable at 23 passing beneath the pulley 11 and downwardly under the guide pulley 24 while the cable at 22 passes under the pulley 10. The portions 21 and 23 of the cable are fastened together at 25 in close proximity to the pulley 15.

In Fig. 4 the cable A is illustrated as being fastened at 26 and 27 to opposite sides of the pulley 15. This pulley 15 is illustrated in Figs. 1 and 2 as having fastened thereon the normally vertically extending arm 28. In Fig. 5 this arm 28 is illustrated as having been engaged by a wiper member 29 carried by an approaching train, not illustrated, and moved for causing the pulley 15 to be rotated to draw the cable, as illustrated. This drawing of one of the sides of the cable will cause both of the cable parts 21 and 23 to be pulled upon, due to the connection 25. This pulling upon both of the cable parts 21 and 23 will cause the gate arms 8 to be moved into their operative or roadway closing positions.

It is to be understood that this arm 28 and pulley 15 are distantly removed from the gate arms 8, and, in view of this fact, after the last car carrying a wiper 29 has passed over the arm 28 and while the train would still be passing the roadway 6, the gate arms 8 would be permitted to move into their inoperative or roadway opening positions. To overcome this undesirable condition, the shaft 30 carrying the pulley 15 has keyed thereto, see Figure 8, a grooved pulley 31 which has one end of a cable 32 fastened thereto. This cable extends to the grooved pulley 34 which is loosely mounted upon the shaft 35 supporting the grooved pulley 11. This grooved pulley 34 has mounted thereupon a normally vertically extending arm 36. It will now be seen that due to the engagement of the arm 36 by the wipers 29

carried by the train cars, the pulley 15 will be retained in its operated position even after the train wipers have passed over its arm 28.

5 In Fig. 3 the gate arms on the opposite side of the track are shown. These arms are connected to the ends 19^a of a second cable B which extends downwardly to pass around the pulleys 12 and 13 and from them 10 to the distantly removed pulleys 16 and 18 which the cable passes around and returns to and beneath the pulleys 12 and 13 to its united or unbroken portion beneath the crossing 6. The parts of the cable in close 15 proximity to the pulley 18 are connected together at 25^a and are connected at 26^a and 27^a to opposite sides of the pulley 18. It will now be seen that by rotating the pulley 18 by the arm 18^a in either direction, the 20 cable portions will be pulled upon for moving the gate arms 8 into their roadway closing or operative positions in the same manner and for the same result as the above described arms 28 and 36 operate.

25 For the purpose of connecting the cables on the opposite sides of the track 5 for causing the actuation of one to actuate the other, the pulleys 17 and 18 have their supporting shafts 37 provided with sprocket 30 wheels 38 upon which ride the sprocket chains 39 which also travel over the sprocket wheels 40 mounted upon the opposite ends of the single shaft 41.

Fig. 9 is intended to illustrate the possibility of connecting the distantly removed pulleys 15 and 16 by similar sprocket wheels 38^a, sprocket chains 39^a, shaft 41^a, and sprocket wheels 40^a.

It is to be understood that the forms of 40 this invention herewith shown and described are to be taken as preferred examples of the same, and that various changes in the shape, size, and arrangement of parts may be resorted to without departing from the 45 spirit of the invention or the scope of the subjoined claims.

Having thus described the invention, I claim:—

1. In a device of the type described, the 50 combination with a railway track, of a pair of spaced posts on each side of said track, a gate arm pivoted to each post, a cable for each side of said track connected at its free ends to said gate arms, means for movably supporting the intermediate portions of said cables to permit the latter to extend to distant points along the track, and means 55 adapted to be controlled by an approaching train for moving said cables to cause the train for moving said cables to cause the 60 arms to be moved into their operative positions.

2. In a device of the type described, the

combination with a railway track, of a pair of spaced posts on each side of said track, a gate arm pivoted to each post, a cable for 65 each side of said track connected at its free ends to said gate arms, means for movably supporting said cables to permit the latter to extend to distant points along both sides of the track, means adapted to be controlled by an approaching train for moving one of said 70 cables to cause the arms connected thereto to be moved into their operative positions, and means for operatively connecting the second cable to the cable actuated by the 75 train.

3. In a device of the type described, the combination with a railway track, of a pair of spaced posts on each side of said track, a gate arm pivoted to each post, a cable for 80 each side of said track connected at its free ends to said gate arms, means for movably supporting said cables to permit the latter to extend to distant points along both sides of the track, means for connecting together 85 different portions of each cable so that movement of a cable will cause both of the free ends of the same to pull in the same direction upon the gate arms connected thereto for moving both gate arms into their 90 operative positions, means adapted to be controlled by an approaching train for moving said cables to cause the arms to be moved into their operative positions, means actuated by the train when passing the gate 95 for causing the arms to remain in their operative positions until the train has passed.

4. In a device of the type described, the combination with a railway track, of a pair of spaced posts on each side of said track, a gate arm pivoted to each post, a cable for each side of said track connected at its free ends to said gate arms, means for movably supporting said cables to permit the latter to extend to distant points along both sides 105 of the track, means for connecting together different portions of each cable so that movement of a cable will cause both of the free ends of the same to pull in the same direction upon the gate arms connected thereto for moving both gate arms into their operative positions, means adapted to be controlled by an approaching train for moving one of said cables to cause the arms connected thereto to be moved into their operative positions, means for operatively connecting the second cable to the cable actuated by the train, and means actuated by the train while passing the gate for causing the arms to remain operative until the train has 120 passed.

In testimony whereof I affix my signature.

STEVE KOLARIES.
